JOGGLING TOOL

Filed June 11, 1943

UNITED STATES PATENT OFFICE

2,363,931

JOGLLING TOOL

Charles L. Beard, Lancaster, Pa.

Application June 11, 1943, Serial No. 490,471

1 Claim. (Cl. 153—21)

My invention relates to improvements in offset dies, for forming offset or depressed portions in opposite ends of pieces of metal of angular shape or in form of strips, so that a number of such pieces may be secured together in overlapping uniplanar arrangement.

The principal object of the invention is to provide such a device having a minimum of structural parts requiring movement or adjustment during the placing of work therein or removal of the same therefrom.

A further object of the invention is to provide an efficient die construction in which flat strips or right angularly bent metal pieces can be readily inserted and as readily removed therefrom.

A still further object is to provide a die construction adapted to offset one end of a metal piece inserted in one side thereof and to offset the other end of the piece when the latter is inserted in the opposite side thereof.

Objects and advantages, and features of invention in addition to those mentioned will appear from the construction, and combination of parts hereinafter described and shown in the drawing, wherein:

Figure 1 is a perspective view showing the dies in side by side relation assumed when used in a vise and showing in dotted and full lines an angle work strip before being jogged;

Figure 2 is a section taken on the line 2—2 of Figure 1, showing the die in open or unclamped position;

Figure 3 is a view similar to Figure 2, but showing the dies closed or in clamped position;

Figure 4 is a section taken on line 4—4 of Figure 3;

Figure 5 is a section taken on line 4—4 of Figure 4 but with the dies reversed;

Figure 6 is a plan view of an angle strip jogged at both ends and showing straight angled strips overlapping these ends; and

Figure 7 is a detailed perspective showing an angle strip jogged at both ends and showing a second angle strip placed in overlapping relation to one end of the jogged strip.

Referring more particularly to the drawing 1 denotes a die construction comprising what, for convenience, may be termed upper and lower rectangular die members 2 and 3 respectively. These members are formed with vertically disposed registering openings 4, for loosely accommodating bolts 5. The bolts 5 are provided with threaded portions 6 at each end thereof to removably receive correspondingly threaded nuts 7, and are somewhat longer than the combined

height of the superimposed die members, thus permitting relative vertical movement of these latter members away from or toward each other, within the confines of the nuts, after the latter have been applied, for a purpose hereinafter explained.

The base or bottom die member 3 is formed with spaced parallel and horizontally disposed threaded openings 8, at each side thereof. Bolts 9, extend into these openings and hold a pair of side plates 11 and 11', in place. The plates 11 and 11' are formed along their inner lower ends with narrow flanges 12 which serve to space the inner faces of the plates a slight distance from the sides of the die member 3, thus forming narrow open ended side pockets 15 and 15', also for a purpose presently described.

The opposing upper and lower die members are respectively provided with working faces 16 and 16' and adjacent recesses or cut away portions 17 and 17', these parts being staggered, that is, the working face 16 of the upper die member 2 is opposed to the cut away portion 17' of the lower die member 3, the working face 16' of the latter being positioned opposite the recessed portion 17 of the upper die member. The construction thus described when placed in a suitable vise 30, is ready to form offsets in a piece of angle-shaped material 18, as illustrated in Figure 1. The jaws of the vise 30 are shown in side by side relation whereas it will be obvious that these jaws could be vertically disposed and that the die assembly could be placed in a conventional press instead of a vise.

35 In practice one leg or web 19, of the angle work piece 18, which may be termed the horizontally disposed web, is placed between the die members with its end overlying one side of the cut away or recessed portion 17' of the lower die member, the other leg or web 20 being snugly received within the side pocket 15, which for convenience will be designated the right side pocket. The assembly is now placed in the vise 30 and pressure applied to cause the working face 16 of the upper die member to force the end portion of web 19 downwardly into the recess 17' of the lower die member 3, thus forming the desired offset 21, in an obvious manner. The piece of material 18 is now removed and the opposite end of the web 19 inserted between the die members in overlying relation with respect to the other side of the cut away or recessed portion 17' of the lower die member, and the leg or web 20 snugly held in the left hand side pocket 15'. The die members 2 and 3 are again clamped tightly to-

gether in the vise, and this end of the work is jogged at 22 in the same manner as the previously jogged end 21. The depth of the recesses 17-17' is such that when the offset end of one piece of work is placed in overlapping relation with respect to the offset end of a similar jogged piece, the connected sections will lie in a uniform plane. It will be obvious that the side plates 11, 11' can be adjusted within certain limits to increase the width of pockets 15-15' for the accommodation of work pieces formed from sheet metal of different thicknesses. This is also true with respect to the spacing of the die members.

Insertion between and removal of the work piece 18 from the dies can readily be effected by sliding the piece in a rearwardly or forwardly direction, with respect to the die members, according to which end of the work piece is being offset or jogged, it being merely necessary to lift the upper die member away from the lower die member during these operations. Due to the fact that the pockets 15-15' are open at their ends they offer no obstacle to the insertion therein or removal of the vertically disposed webs 20 therefrom.

It may be noted here that the upper side edges of the lower die member 3 are beveled at 25, to compensate for angle pieces of different radii, that is, eliminate the danger of disturbing the radius of the work piece when the joggle is made.

While the die members have been described as being upper and lower members and the plates 11-11' as side plates it should be noted that these terms are relative and have been used rather loosely and as applying more particularly to the parts prior to placing the die members in the vise. When the assembly is placed in a vise the jaws of which are disposed in side by side rela-

tion the die members will of course preferably be similarly disposed.

While the foregoing description is directed to the joggling of angularly shaped work, it will be obvious that the invention is adapted for joggling flat strips and that the latter are received between and acted upon by the jaws 2 and 3, in the same manner that the flange 19, of angle piece 18, is received between and jogged by these jaws. Further description is therefore deemed unnecessary.

Having thus described my invention:

What I claim is:

15 In an apparatus for deforming angle shaped strips of metal, a pair of opposed die members, means for securing said die members together for relative movement toward and away from each other, side plates adjustably secured to the sides of one of said die members, a flange extending along one edge of each of said side plates for maintaining them in spaced relation to said sides to form pockets, one of said pockets between said plates and said sides adapted to slidably receive one leg of an angle shaped strip when the other 20 leg thereof is slidably inserted endwise between the die members, at one side thereof, and the other pocket adapted to receive said one leg when said other leg is slidably inserted between the die members at the other side thereof, said 25 die members each having a working surface extending from side to side thereof and disposed in offset opposition to each other for joggling one or the other of the respective ends of said other leg upon relative movement of said die members 30 toward each other according to which of the side pockets said one leg is inserted in.

CHARLES L. BEARD.
